CLAIM

The ornamental design for a cleaning agent cartridge as shown and described.

DESCRIPTION

FIG. 1 is a front, top perspective view of a cleaning agent cartridge.

FIG. 2 is a rear, bottom perspective view of the cleaning agent cartridge of FIG. 1.

FIG. 3 is a front elevation view of the cleaning agent cartridge of FIG. 1.

FIG. 4 is a rear elevation view of the cleaning agent cartridge of FIG. 1.

FIG. 5 is a right side view of the cleaning agent cartridge of FIG. 1.

FIG. 6 is a left side elevation view of the cleaning agent cartridge of FIG. 1.

FIG. 7 is a top plan view of the cleaning agent cartridge of FIG. 1; and,

FIG. 8 is a bottom plan view of the cleaning agent cartridge of FIG. 1.

The broken lines in FIGS. 1-8 illustrate portions of the cleaning agent cartridge that form no part of the claimed design.

1 Claim, 7 Drawing Sheets
